UNITED STATES PATENT OFFICE.

TRYGVE IVERSEN, OF CHICAGO, ILLINOIS.

MILK-BOTTLE CONTAINER.

Application filed August 16, 1926. Serial No. 129,831.

My invention relates to milk bottle containers and it is the object of my invention to provide a new and improved form and arrangement of device of this type for receiving and protecting bottles of milk and cream as they are left by a milkman on early morning deliveries. It is one of the objects of my invention to provide an improved construction of device of this type in which 10 a combination latching and locking means is provided adapted by a preliminary movement to secure the door of the container releasably in closed position and adapted by a continued movement to effect a locking of 15 the door, the margin of movement between the initial latching and the final locking being preferably quite large so as to prevent accidental locking of the device. It is another object of my invention to improve the 20 form of the container so as to utilize the wall of the building or other support for the back face of the container whereby the cost of the structure is reduced. It is another object of my invention to improve 25 generally the form of the locking means.

It is another object of my invention to improve devices of this type in sundry details hereinafter pointed out. The preferred means by which I have accomplished my 30 several objects are illustrated in the drawings and are hereinafter specifically described. That which I believe to be new and desire to cover by Letters Patent is set forth in the claims.

35 In the drawings,—

Fig. 1 is a perspective view of my improved device in position upon a wall, one corner of the container being broken away for clearness of illustration.

40 Fig. 2 is an inside face view of the door of my improved device, as seen at the line 2—2 of Fig. 1, and showing in dotted lines a milk card secured removably in position on the door.

45 Fig. 3 is a vertical cross section through my device, taken at line 3—3 of Fig. 1, showing diagrammatically a bottle of milk in position in the container, and showing in dotted lines a changed position of the door.

50 Fig. 4 is a vertical sectional view, taken substantially at line 4—4 of Fig. 3 but with the rotary locking member rotated through a half revolution as compared with the position shown in said Fig. 3; and

55 Fig. 5 is a perspective view of a rotary member of the locking mechanism.

Referring to the several figures in which corresponding parts are indicated by the same reference characters, 10 indicates a housing in the form of a box-like shell made 60 of sheet metal, the shell being provided with an inwardly extending flange 11 at the rear face, being secured in position upon a wall 12 by means of screws 13 passing through suitable openings in the flange 11. The front 65 face of the shell 10 is closed by a door 14 also formed of sheet metal and hingedly connected along its lower edge with the shell 10, the arrangement being such that the door 14 when closed completes the enclosure. 70 Links 15 are pivotally connected with the door 14 on its inner face, extending through clips 16 carried by the shell 10 in such position that hooks 17 on the ends of the links are adapted by engagement with the clips 75 16 to hold the door 14 in horizontal position as shown in dotted lines in Fig. 3. The door 14 is also provided on its inner face with leaf springs 18 each rigidly connected in position at one end so as to hold removably in position a milk card 19 as shown in 80 Fig. 2.

Upon the inner face of the top ply of the housing 10, I have provided a reinforcing bar 20 rigidly secured in position and provided at its forward end with a downwardly and rearwardly turned hook portion 20^a which is adapted to be used as hereinafter described for securing the door 14 in closed 90 position.

Upon the front face of the door 14, I have provided a vertically disposed reinforcing bar 21 which is rigidly secured in position upon the face of the door. Near the upper edge of the door 14, I have mounted a knob 22 which is rigidly secured in any suitable manner upon a square shaft 23 which extends through the opening in a bushing 24 revolvably mounted in suitable openings 100 through the door 14 and the bar 21. Upon the inner square end of the shaft 23 I have provided a disk locking member 25 which is supported by the shaft and is rotatable therewith, being secured in position upon the shaft by a washer 26 and a nut 27 which is secured by means of screw threads upon the inner end of the shaft 23. The disk 25 is provided at its outer edge with a flange 28, the rear edge of which is rolled outwardly and backwardly upon itself so as to provide in effect a substantially annular hook about the disk 25. The rolled portion is cut away 105 110

at one point, however, as indicated at 29 (see Fig. 5) so as to permit the flange 28 to be brought into the position as shown in Fig. 3 for operative engagement with the hook 20 when the disk 25 is rotated through the medium of the knob 22. As will be readily understood, upon a slight movement of the disk 25 in clockwise direction in Fig. 4 from the position there shown, the flange 28 is brought into operative engagement with the hook 20 so as to secure the door 14 releasably in closed position. With the disk 25 rotated a short distance in clockwise direction from the position shown in Fig. 4, the door 14 is held tightly in closed position but can be again released for opening by merely rotating the disk 25 in the reverse direction into the position shown in Fig. 4.

Upon the inner face of the door 14 below the disk 25, I have mounted a lock 30 of any approved type adapted to be operated by a key inserted through an opening 31 in the door and the bar 21 as shown in Fig. 1. When the disk 25 is in the position as shown in Fig. 4, the bolt 32 of the lock 30 stands in engagement with the flange 28 by which the movement of the bolt is limited. When, however, the disk 25 is given a half revolution from the position shown in Fig. 4, an opening 33 through the flange 28 opposite the notch 29 in the rolled portion of the flange is brought into registration with the bolt 32 so as to permit the extension of the bolt into the position as shown in Figs. 2 and 3. The bolt 32 then serves to hold the disk 25 against rotation whereby the door 14 is held firmly in closed position by the engagement of the rolled portion of the flange 28 with the hook 20.

For limiting the rotation of the rotary disk member 25, I have provided an arc-shaped slot 34 in the disk at one side thereof in which a lug 35 carried by the door 14 operates for controlling the movement of the disk.

For indicating the condition of the locking means, I have provided a plate 36 mounted upon the squared shaft 23 between the knob 22 and the bar 21, such plate 36 being provided at one side with a pointer 37. When the parts are in the position shown in Fig. 2, the pointer 37 stands in the position shown in Fig. 1 pointing toward the word Locked. When the mechanism has been turned to the position as illustrated in Fig. 4, it will be understood that the pointer will extend toward the right in Fig. 1 toward the word Open.

In the use of my improved device, the mechanism is to be left in a position in which the rolled portion of the flange 28 is in engagement with the hook 20 but in which the bolt 32 is not in engagement with the opening 33. When the milkman comes to make his deliveries, he is able to open the door 14 readily so as to place a bottle 38 in position within the housing. He then closes the door and gives the knob 22 a rotary movement in clockwise direction in Fig. 1 to the limit of the movement until the bolt 32 engages the opening 33 for locking the disk 25 against reverse movement. The contents of the box are thus afforded the desired protection until they are removed by the use of a key as will be readily understood.

While I prefer to employ the form of construction as shown in my drawings and as above described, it will be understood that I do not wish to be limited to the details of the construction except so far as certain of the claims are specifically so limited, inasmuch as it is evident that changes may well be made in the construction without departing from my invention.

I claim:

1. In a device of the type described, the combination of housing means adapted completely to enclose the contents and comprising a pivotally mounted door, a hooked member mounted on the body of said housing, a disk revolvably mounted on the door, hook means carried by the disk adapted upon a slight rotation when the door is closed to engage said hooked member, and locking means mounted on the door adapted upon continued rotation of the disk to lock the disk against reverse movement.

2. In a device of the type described, the combination of housing means adapted completely to enclose the contents and comprising a door pivotally mounted on the body of the housing, a hook carried by the body of the housing having its end portion turned inwardly and backwardly adjacent to the free edge of the door, a member rotatably mounted on said door and comprising a flange turned outwardly and forwardly, said flange being cut out at one side for enabling it to be turned into operative engagement with said hook, and locking means mounted on the door adapted at one position of the rotary member automatically to lock said member against rotation.

TRYGVE IVERSEN.
